UNITED STATES PATENT OFFICE.

FRED FRAZER, OF SYRACUSE, NEW YORK.

DESIGN FOR A BELT-BUCKLE.

SPECIFICATION forming part of Design No. 19,343, dated October 8, 1889.

Application filed September 11, 1889. Serial No. 323,652. Term of patent 7 years.

To all whom it may concern:

Be it known that I, FRED FRAZER, a citizen of the United States, residing at Syracuse, in the county of Onondaga and State of New York, have invented and produced a new and original Design for a Belt-Buckle; and I do hereby declare the following to be a full, clear, and exact description of the same, reference being had to the accompanying drawings, forming a part thereof.

In the accompanying drawings, Figure 1 is a plan view of a belt-buckle showing my design. Fig. 2 is a like view showing a modification in the construction of the buckle.

The buckle constructed according to my design is formed of the two parts A and A', each part being provided at its outward end with a loop a and converging bars c, extending to the center of the buckle. The bars c of the main part A carry a head B, which is in the form of a bat or racket—such as is commonly used in the game commonly known as "lawn tennis"—a shank or handle b ex-

tending rearward from the head B, as shown. The arms or bars c of the part A' are joined at their inward ends, where they are formed with a groove or cavity to receive the neck e of the head B when the two parts of the buckle are connected. The head B is provided with two ears or lugs d, and when the parts of the buckle are adjusted, as shown in the drawings, the said lugs d extend under the arms c of the part A', and the two parts are thus securely connected. When the belt is on the person and secured by the buckle, the figure 35 of the racket appears in position along the center of the buckle.

I claim—

A design for buckles, substantially as herein shown and described.

In testimony whereof I have affixed my signature in presence of two witnesses.

FRED FRAZER.
